UNITED STATES PATENT OFFICE.

ALLEN COLBY, OF BRUNSWICK, MAINE.

DERRICK.

SPECIFICATION forming part of Letters Patent No. 448,321, dated March 17, 1891.

Application filed October 25, 1890. Serial No. 369,291. (No model.)

To all whom it may concern:

Be it known that I, ALLEN COLBY, a citizen of the United States, residing at Brunswick, in the county of Cumberland and State of Maine, have invented certain new and useful Improvements in Derricks; and I do hereby declare the following to be a full, clear, and exact description of the invention, such as will enable others skilled in the art to which it applies to make and use the same.

My invention relates to derricks for raising and moving heavy articles from one place to another; and it is designed particularly for loading and unloading cars.

15 In carrying out my invention I build an elevated track, which extends over one or more of the car-tracks, and on this elevated track runs a traveler. The traveler has a windlass which operates a fall, the fall passing through a system of purchase-blocks and sheaves, by which the power of the windlass is greatly increased. For a fall I make use of a chain, which passes over a sprocket-wheel on the windlass and is held in place on said 20 sprocket-wheel by means of a guide-pulley, which is pivoted adjacent to the drum and holds the chain in contact with the drum. The traveler is moved on its track by means of a chain which is secured at the extremities 25 of the track and passes over a sprocket-wheel operated by a windlass.

I have illustrated my invention by means of the accompanying drawings, in which—

Figure 1 is a section on the line $x-x$ of Fig. 35 2, and Fig. 2 is a plan or top view.

A represents an elevated track supported on posts $a a$. This track is built of sufficient length to extend over the space within which the derrick is to operate. For instance, for rail-road-work it would extend across one or more of the railroad-tracks and over the platform or space where the teams are to stand while being loaded. Running on this elevated track A is a traveler B, supported by trucks b. This 45 traveler is built of any desired shape to accommodate the various bearings necessary for the windlasses and purchase-blocks. The hoisting-gear is operated by a windlass of which C is the gear and D the pinion, d the 50 crank-shaft, and d' the crank. On the main shaft c is a sprocket wheel or drum c^3 , having a groove in its periphery which receives

and holds the chain G, which is used for a fall. A pawl or dog c' is provided to engage the gear C. To prevent any possibility of the 55 chain slipping, I provide a guide-pulley c^3 immediately beneath the sprocket-wheel c^3 , the perimeters of the two wheels coming near together with just room enough for the chain to pass between them. The chain is thus held 60 continually in contact with the sprocket-wheel, and is thus prevented from working out and slipping. A box F is placed under the windlass to receive the chain.

I get my purchase in the derrick, as here 65 shown, by means of a double purchase-block K and two sheaves ee, mounted on the frame of the traveler. The block K has two sheaves k and k' , pivoted one over the other. The fall passes through the block and over the 70 fixed sheaves, and its end is secured, as here shown, to the block K. A hook k^2 is secured to the block for convenience in hooking onto various articles.

Means are provided for moving the traveler 75 along the track. For this purpose I make use of a windlass, of which h^2 is the crank, i the crank-shaft, I the pinion, II the gear, h' the main shaft, and h the drum, which is formed like a sprocket-wheel to receive the chain J 80 and hold it. The chain J passes over the pulleys h^2 , mounted at the lower part of the traveler in a bracket. The chain J extends in each direction, and each end is secured to a stud or similar piece j' at the end of the 85 track. It is obvious that by working the windlass II the traveler is carried in either direction.

The operation of my device will be readily seen from its construction.

One man operating by means of my derrick can readily handle the heaviest articles in loading and unloading cars and doing similar work. Having raised the weight with one windlass, he moves the traveler to the desired 95 position by means of the other and there deposits it.

The device is, as explained, admirably adapted for the use of railroads where heavy freight is to be handled.

I claim—

1. In a derrick, an elevated track, a traveler running thereon, a windlass on said traveler having a sprocket-drum, a chain running

over said drum, a block connected by said chain with a pair of sheaves mounted on the traveler, and a guiding-pulley mounted adjacent to said drum, the said pulley and drum 5 having their peripheries contiguous, whereby said chain is held in place on said drum, substantially as described.

2. In a derrick, a track and a traveler running thereon, a windlass on said traveler, a 10 pair of sheaves mounted on said traveler, and a block, said sheaves and block connected with said windlass for hoisting heavy articles, a sec-

ond windlass B, having a sprocket-drum, and a chain running over said drum and over suitable guiding-pulleys and secured at its ends 15 to the extremities of the said track, whereby said traveler may be moved on said track, substantially as described.

In testimony whereof I affix my signature in presence of two witnesses.

ALLEN COLBY.
